(57) **CLAIM**

The ornamental design for a light fixture including a non-opaque light cover secured to a light fixture body, as shown and described.

DESCRIPTION

FIG. 1 is a perspective view of a light fixture including a non-opaque light cover secured to a light fixture body showing the new design;

FIG. 2 is a front elevational view of the light fixture, the back, left, and right elevational views being identical to the front elevational view;

FIG. 3 is a top plan view of the light fixture; and,

FIG. 4 is a bottom plan view of the light fixture, openings in a bottom of the light fixture body being shown in broken lines. The broken lines shown on the drawings depict portions of the light fixture that form no part of the claimed design.
